VENTILATOR

Filed Sept. 12, 1930

UNITED STATES PATENT OFFICE

HAROLD B. HAWES, OF FAIRFIELD, CONNECTICUT, ASSIGNOR TO G. DROUVE CO., OF FAIRFIELD, CONNECTICUT, A CORPORATION OF CONNECTICUT

VENTILATOR

Application filed September 12, 1930. Serial No. 481,369.

My invention relates to ventilators such as are used in factories or large buildings, and has for its object to provide a multiple sealing means for preventing the ingress of rain, sleet, snow, dirt or other objectionable matter when the ventilator is closed, to prevent rattling, and to offer a construction such as may be easily operated irrespective of the nature of the roof of the building.

This invention is a ventilating structure and has nothing whatever to do with the roof except that the latter affords a means of support, and, as it is advisable to show the ventilator as applied to a building, I have elected to show my improvement mounted on a skylight structure which latter is so well known that it will be referred to as an ordinary roof structure element.

Referring to the accompanying drawings, Figure 1 is a side elevation showing my invention mounted on a skylight structure the latter being broken away.

Figure 2 is a section at the line 2—2 of Figure 1, showing the ventilator closed, and Figure 3 is a view similar to Figure 2 with the ventilator open.

Similar numerals of reference will be used to denote like parts in the several figures of the drawings.

The superstructure of the ventilator comprises a plurality of spaced generally diverging frame supports 1, preferably integral with a roof portion 2, and the lower ends of these supports are secured in any suitable manner as by bolts 3 to a part of the roof structure of the building, in the present instance to angle bars 4 which latter support the skylight or other roof portion 5 of the building.

The roof portions 4 rest upon the ends of cross-struts 6 (only one shown) the latter affording a brace for the supports 1, and these portions 4 are secured in any suitable manner to said struts, as by bolts 7.

Bolted to the roof portion 2 is a metal sheet 8, and spaced guides 9 are bolted at the top and bottom respectively to the parts 2 and 6, and a hanger 10 is also bolted to the part 2 within which hanger a pulley 11 is journaled.

12 is an elongated metal bar within the space between the guides 9, and connected to this bar, as by a ring 13, is a rope or cable 14 which is passed up over the pulley 11 and thence downwardly, so as to be convenient of access.

15 are ears secured to the bar 12 at suitable intervals, 16 are the ventilator closures pivotally swung at their upper ends at 17 from the side edges of the sheet 8, and to the inner faces of these closures 16 are bolted ears 18, and the extremities of levers 19 are pivoted to these ears 15 and 18, so that it will be clear that when the cable 14 is pulled downwardly the bar 12 will be elevated and the closures swung to the open position shown at Figure 3.

The frame supports 1, roof portion 2, cross-struts 6 and guides 9, constitute one unit of the ventilator construction, and there are as many of these units as desirable and they are spaced apart, and it is between these units that the air passes for the purposes of ventilation, but the drawings show but one of these units, since further illustration in this respect would be mere duplication.

But the sheet 8, the closures 16, angle bars or roof supports 4, roof portions 5 and bar 12, all extend the full length of the ventilator opening, although in very long openings, it is sometimes advisable to subdivide the ventilating closures and operate them as independent sections, and in cases like this the changes that would be made are quite obvious.

Secured to the lower outer portions of the frames 1 are sheet metal strips 20 which extend the full length of the ventilator opening and are resilient, the upper edges being formed into seats 21 while the lower edges extend along the roof portions 5 and are in close contact therewith so as to form flashings 22.

The closures 16, when no ventilation is desired, are forced tightly against the seats 21 by the weight of the bar 12, and as these seats are resilient the sealing of this point is efficient.

But the lower ends of the closures are bent inwardly and outwardly so as to form angular parts 23 that are in close proximity to

the metal strips 20, so that, if the seats 21 are stressed unduly the parts 23 will seat against the strips 20, and the lower extremities 24 will seat against the flashings 22, thus affording multiple sealings for the closures.

I desire to particularly lay stress on the fact that my invention has nothing whatever to do with any particular kind of roof to a building, it being merely necessary, of course, that the building should have the usual ventilating opening over which my improved ventilator is mounted as hereinbefore described, and that pairs of frame supports 1 are spaced apart throughout the length of this opening. The metal roof portion 8, the metal sealing strips 20, the bar 12 and the closures 16 all extending the full length of said opening, and there can be as many connections for elevating this bar as desired, and it is further to be noted that the bar may be pushed upward by any ordinary means applied from below, it being merely necessary that the bar should be freely suspended when the ventilator is closed so as to exert a constant force to insure the resilient sealing contacts of the closures with the seating portions carried by the strip 20, in the manner hereinbefore described.

It is not necessary that a special roof 8 be provided, since the top portion 2 of the frames 1 may extend the length of the ventilator opening and the side frames themselves bolted thereto or even made integral therewith, and, as far as the pivotal points 17 are concerned, these may be provided by bolting suitable eyes to the top of the frame structure or by so forming the latter as to readily afford pivotal connections for the closures, this being a matter fully within the scope of ordinary mechanical judgment, but the structure shown in the drawings is preferred, since it is water and dirt proof.

What is claimed is:—

1. In a ventilating structure for roofs having ventilating openings, of spaced frames secured to the sides of said opening, having a roof portion rigid with the tops thereof and extending the length of said opening, multiple resilient sealing seats secured to said frames and extending the length of said opening, ventilator closures pivotally swung at their upper edges by intercurling the edge of the roof portion and the closure and carrying multiple sealing parts for contacting with the seats when the ventilator is closed, and means for operating said closures.

2. A ventilating structure for application to openings in roofs, comprising a superstructure secured to the roof opening and consisting of spaced frames, a roof portion rigid with the top of the superstructure, sealing seats carried by the lower side edges of said superstructure, ventilator closures swung from the edge of the roof portion by

intercurling the edge thereof with the closure and carrying multiple resilient seating members adapted to cooperate with said seats when the ventilator is closed, and means for operating said closures.

3. A construction as in claim 2, further distinguished in that said means consists of an elongated metal bar, arranged with said closures so as to stress the sealing contacts between the closures and superstructure.

In testimony whereof I affix my signature hereto.

HAROLD B. HAWES.
